CARRIER FOR SKI ACCESSORIES

Hjalmar J. Kallman, Chicago, Ill., assignor to Stephen J. Turk, Chicago, Ill.

Filed Aug. 16, 1963, Ser. No. 76,234

Term of patent 14 years

(Cl. D87—5)

Fig. 3.

FIG. 1 is a perspective view of a carrier for ski accessories showing my new design;

FIG. 2 is a left-side elevational view thereof; and

FIG. 3 is a top plan view thereof.

The face opposite that shown in FIG. 1 is substantially plain and unornamented.

I claim:

The ornamental design for a carrier for ski accessories, substantially as shown and described.
